DESIGN FOR A FIGURE TOY

Jacob H. Miller, Cresson, Pa.

Application April 5, 1944, Serial No. 113,154

Term of patent 14 years

(Cl. D34—15)

To all whom it may concern:

Be it known that I, Jacob H. Miller, a citizen of the United States of America, residing at Cresson, county of Cambria, and State of Pennsylvania, have invented a new, original, and ornamental Design for a Figure Toy, of which the following is a specification, reference being had to the accompanying drawing, forming a part thereof, wherein:

I claim:

The ornamental design for a figure toy, as shown.

JACOB H. MILLER.
